UNITED STATES PATENT OFFICE

140,626

DESIGN FOR A FLAG DISPLAY STAND OR SIMILAR ARTICLE

Andrew J. Olay, Flint, Mich.

Application November 1, 1944, Serial No. 116,084

Term of patent 14 years

(Cl. D80—9)

To all whom it may concern:

Be it known that I, Andrew J. Olay, a citizen of the United States, residing at Flint, in the county of Genesee and State of Michigan, have invented a new, original, and ornamental Design for a Flag Display Stand or Similar Article, of which the following is a specification, reference being had to the accompanying drawing, forming part thereof.

I claim:

The ornamental design for a flag display stand or similar article, as shown.

ANDREW J. OLAY.
